UNITED STATES PATENT OFFICE.

RICHARD E. JONES AND GEORGE A. MARTIN, OF PEARL RIVER, NEW YORK, ASSIGNEES
TO DEXTER FOLDER COMPANY, OF PEARL RIVER, NEW YORK, A CORPORATION
OF NEW YORK.

SLOW-DOWN AND SHEET-STRAIGHTENING DEVICE.

Specification of Letters Patent. Patented Apr. 13, 1915.

1,135,811.

Application filed March 25, 1914. Serial No. 827,179.

To all whom it may concern:

Be it known that we, RICHARD E. JONES and GEORGE A. MARTIN, citizens of the United States, and both residing at Pearl River, in the county of Rockland, State of New York, have invented certain new and useful Improvements in Slow-Down and Sheet-Straightening Devices, of which the following is a full and clear specification.

This invention relates to sheet-feeding machines and has for its primary object to provide an improved construction for combined sheet-straightening and slow down devices.

The particular features of the invention are pointed out in the appended claims, reference being had to the accompanying drawings which exemplify our invention in a preferred embodiment.

In the drawings, Figure 1 is a side elevation of a portion of a sheet-feeding machine, embodying our improvements, parts being broken away and parts shown in section; Fig. 2 is a top plan view of the same, parts

being broken away and parts shown in section; Fig. 3 is a rear end elevation of the same; Fig. 4 is a diagrammatic top plan view of a feeding machine provided with our improvements; Fig. 5 is a fragmentary side elevation of a modification, parts being broken away and parts shown in section.

Referring first to Fig. 4, 1 and 2 designate devices arranged adjacent opposite edges of a feeding machine, their functions being to engage the opposite edges of a sheet which is being fed forwardly by the tapes 3 across the feed board 4. Supposing, for example, that sheets are being fed to the cylinder 5 of a printing press, the devices 1 and 2 are under the control of sheet-actuated means for regulating the amount of movement of each edge of a sheet relatively to that of the other edge. By this means the sheet is properly registered to be delivered to the grippers of the printing press. The detail construction of each of the devices 1 and 2 will be understood from an inspection of Figs. 1, 2, 3 and 5.

Referring to Fig. 1, the tapes 3 pass about the tape roller 6 on the shaft 7, said shaft being suitably disposed to adapt the tapes 3 to deliver sheets upon a table or plate 8. The upper surface of the plate or table 8 is adapted in the present embodiment to co-

operate with the peripheral surface of a roller 9 which is mounted upon a spindle 10 carried by the lower end of a lever arm 11, said lever arm being keyed to a rock shaft 12. A cam arm 13 which is also keyed to the rock shaft 12 carries a cam roller 14 which runs on a cam 15, said cam being keyed to a shaft 16 which rotates in the direction indicated by the arrow. When the parts are in the positions shown in Fig. 1, the cam roller 14 travels over the inner run 65 of the cam 15 and permits the roller 9 to run upon the plate or table 8 or the sheet traveling thereover. In order to provide suitable means for driving the roller 9 so that its periphery will travel forwardly 70 with the sheet (which passes thereunder while it is being raised and lowered,) a gear 17 is keyed to the spindle 10 and meshes with a rack bar 18, the rear end of said rack bar being pivotally connected at 19 with 75 the extension 20 of a lever arm 21 which is keyed to a rock shaft 22.

As shown in Figs. 1, 2 and 3 the lever arm 21 carries a laterally projecting pin 23 upon which is journaled the hub 24 of the extension 20. A pin 25 extends through the outer end of the journal pin 23, being adapted to be inserted into any one of a plurality of radial notches 26 provided in an abutment 27 to which one end of a spring 28 is secured, 85 said spring 28 being mounted on the pin 23 and having its other end exerting a pressure on the hub 24 tending to rotate the extension 20 toward the left, according to Fig. 1. The lower end 29 of the arm 21 90 (see Fig. 1) carries a stop pin 30 which limits the displacement of the extension 20 toward the left. The purpose of this construction will be evident from the following description: Power for rocking the shaft 22 95 is provided by an arm 31, the upper end of which is connected by a link 32 with a lever arm 33, which is keyed to a stub shaft 34 journaled in the boss 35. Also keyed to the stub shaft 34 is a cam arm 36 which carries 100 a roller 37 upon a cam 38 which is keyed to the cam shaft 16 and travels therewith in the direction of the arrow. It will be apparent from this description that as the cam roller 37 mounts to the outer run of the cam 38, the rack bar 18 will travel forwardly and rotate the gear 17 in a clockwise direction, together with the roller 9.

A support 39 which depends from the spindle 10, carries a laterally projecting pin or roller 40 upon which the rack bar 18 slides. Moving with the rack bar 18 and spaced laterally therefrom is a ratchet bar 41 which is preferably provided with a hub 42 journaled upon the pin 19 which drives the rack bar 18. Said rack bar and ratchet bar are thus connected to travel together. The forward edge of the bar 41 is provided with ratchet teeth 43 and reciprocates freely on a roller 44 carried by a pin 45 which projects laterally from a fixed bracket 46. A laterally projecting pin 47 serves to journal the hub 48 of a link 49 from the outer end of which projects laterally a pin 50. Journaled upon the pin 50 is a combined pendulum and ratchet pawl, the pendulum 51 of which is heavier than the pawl 52, thus serving to normally hold this member in the position shown in Fig. 1, in which a stop pin 53 which projects from the lower end of the link 49, normally rests against the end wall 54 of an arcuate slot 55, formed in the hub 56 of the pawl and pendulum member. A lug 57 which projects laterally from the bracket 46 serves to support the link 49 in its lower position shown in Fig. 4. An adjustable abutment in the form of a screw 58 serves to limit the upward movement of the link 49 in the manner to be hereinafter pointed out, said screw being threaded in the lug 59 carried by bracket 46.

In the modification shown in Fig. 5, a plate or table 8' is provided with a slot or opening by means of which the roller 9 is permitted to contact with the peripheral surface of a roller 60 which is journaled beneath the plate 8'. In this modification, the peripheral surfaces of the rollers 9 and 60 constitute the relatively movable surfaces which coöperate to slow down and straighten a sheet in the manner to be pointed out.

Referring to Fig. 1, the tapes 3 deliver a sheet to the plate or table 8 at comparatively high speed, the roller 9 at that instant being elevated by the cam roller 14 traveling the outer run of the cam 15. The action of the cam 15 is so timed that shortly after the sheet has come between the roller 9 and the plate 8, said roller 9 falls upon the sheet. At the same time the cam 38 has displaced the cam roller 37 in such a way as to impart a forward drive to the rack bar 18, thus rotating the gear 17 and roller 9. The peripheral speed of the roller 9 is preferably slower than that of the sheet. When the forward edge of the sheet reaches the pendulum 51, said pendulum is displaced and the pawl 52 caused to move into engagement with the ratchet bar 43. Shortly afterward, the forward motion of said ratchet bar, as well as the rack bar 18 is arrested by the link 49 being driven upwardly against the abutment 58 thus bringing the sheet to a

stop. Immediately after the roller 9 is elevated a slight additional movement which serves to bring the forward edge of the sheet against the front gages, is produced by the tapes 3 which still engage the rear edge of the sheet in sufficient degree to impart this additional movement.

In order to avoid undue strains and breakage by the employment of the positively driven mechanism hereinabove described, the yieldable connection between the arm 21 and the extension 20 enables any thrust which is imparted by the cam 38 after the rack bar 18 is arrested, to be absorbed by the spring 28, the abutment 27 with its notches 26 making it possible to adjust the tension of the spring 28 to any desired degree.

We claim:

1. In a combined slow down and sheet straightener for sheet feeding machines, a surface over which paper is fed at relatively high speed, an instrumentality having a surface adapted to engage a sheet traveling over the first said surface, means for operating said instrumentality to impart a movement to the second mentioned surface of less velocity than the velocity of said sheet, said means including a lever comprising relatively movable parts and a yieldable connection between said parts, and means for blocking the movement of said operating means.

2. In a combined slow down and sheet straightener for sheet feeding machines, a surface over which paper is fed at relatively high speed, a slow down roller having its peripheral surface moving in the same direction as the paper is fed over the first said surface, a rack bar geared to said slow down roller, means for reciprocating said rack bar, and sheet actuated means for interrupting the reciprocating movements of said rack bar.

3. In a combined slow down and sheet straightening mechanism for sheet feeding machines, a surface over which the sheets are fed, a roller suitably mounted to co-operate with said surface in retarding the movement of a sheet, an oscillatory arm, a rack bar geared to said roller, said rack bar being also pivotally connected to said oscillatory arm, and sheet actuated means for interrupting the reciprocating movements of said rack bar.

4. In a combined slow down and sheet straightening mechanism for sheet feeding machines, a surface over which the sheets are fed, a roller suitably mounted to co-operate with said surface in retarding the movement of a sheet, an oscillatory arm, a rack bar geared to said roller, said rack bar being also pivotally connected to said oscillatory arm, and sheet actuated means for interrupting the reciprocating movements of said rack bar, said means including a

sheet actuated pendulum, a pawl moved thereby, and a rack bar pivotally connected to said oscillatory arm, and adapted to be engaged by said pawl.

5. In a combined slow down and sheet straightening mechanism for sheet feeding machines, a surface over which the sheets are fed, a roller suitably mounted to co-operate with said surface in retarding the movement of a sheet, an oscillatory arm, a rack bar geared to said roller, said rack bar being also pivotally connected to said oscillatory arm, and sheet actuated means for interrupting the reciprocatory movements of said rack bar, said oscillatory arm comprising relatively movable parts and yieldable means for normally retaining said parts in fixed relation to each other.
10. In a combined slow down and sheet straightening mechanism for sheet feeding machines, a surface over which the sheets are fed, a roller suitably mounted to co-operate with said surface in retarding the movement of a sheet, an oscillatory arm, a rack bar geared to said roller, said rack bar being also pivotally connected to said oscillatory arm, and sheet actuated means for interrupting the reciprocatory movements of said rack bar, said oscillatory arm comprising relatively movable parts connected by a knuckle joint, and a spring for holding said parts in extended position.

15. In a combined slow down and sheet straightening mechanism for sheet feeding machines, a surface over which the sheets are fed, a roller suitably mounted to co-operate with said surface in retarding the movement of a sheet, an oscillatory arm, a rack bar geared to said roller, said rack bar being also pivotally connected to said oscillatory arm, and sheet actuated means for interrupting the reciprocatory movements of said rack bar, said oscillatory arm comprising relatively movable parts connected by a knuckle joint, a spring for holding said parts in extended position, and means for adjusting the tension of said spring.

20. In a combined slow down and sheet straightener for sheet feeding machines, a surface over which paper is fed at relatively high speed, an instrumentality adapted to engage a sheet traveling over said surface, means for moving said instrumentality, said means including a lever comprising pivotally connected parts and a yieldable connection between said parts, and sheet operated means for blocking the movement of said instrumentality.

25. In a combined slow down and sheet straightener for paper feeding machines, a surface over which paper is fed at relatively high speed, a paper engaging roller having a relatively slow peripheral speed, said roller being suitably mounted to be moved into and out of paper engaging position,

paper actuated means for blocking the movement of said roller, and means for rotating said roller including a positively driven lever which is substantially unyielding for transmitting power to said roller when uninterrupted in its movement, said lever being provided with means adapting it to yield when the movement of said roller is blocked.

30. In a combined slow down and sheet straightener for paper feeding machines, a surface over which paper is fed at relatively high speed, a paper engaging roller having a relatively slow peripheral speed, said roller being suitably mounted to be moved into and out of paper engaging position, paper actuated means for blocking the movement of said roller, and means for rotating said roller including a positively driven lever which is substantially unyielding for transmitting power to said roller when uninterrupted in its movement, said lever being provided with means adapting it to yield when the movement of said roller is blocked, said lever comprising relatively movable parts and a yieldable connection therebetween.

35. In a combined slow down and sheet straightener for paper feeding machines, a surface over which paper is fed at relatively high speed, a paper engaging roller having a relatively slow peripheral speed, said roller being suitably mounted to be moved into and out of paper engaging position, paper actuated means for blocking the movement of said roller, and means for rotating said roller including a positively driven lever which is substantially unyielding for transmitting power to said roller when uninterrupted in its movement, said lever comprising relatively movable parts and a yieldable connection therebetween, said connection being yieldable in one direction only.

40. In a combined slow down and a sheet straightening mechanism for sheet feeding machines, a surface over which the sheets are fed, a roller suitably mounted to co-operate with said surface in retarding the movement of a sheet, means for imparting a rotary movement to said roller, means for moving said roller into and out of contact with said sheet, and sheet actuated means for terminating the movement of said movement imparting means.

45. In a combined slow down and sheet straightening mechanism for sheet feeding machines, a surface over which the sheets are fed, a roller suitably mounted to co-operate with said surface in retarding the movement of a sheet, means for imparting a rotary movement to said roller, means for moving said roller into and out of contact with said sheet, sheet actuated means for terminating the movement of said movement

120

125

130

imparting means, said sheet actuated means being adapted to terminate the rotary movement of said roller prior to the removal of said roller from the sheet.

- 5 14. In a sheet feeding machine, a surface over which sheets are fed, a roller adapted to coöperate with said surface, means for moving said roller into and out of contact with a sheet, a reciprocable rack 70
10 geared to said roller, a ratchet partaking of the movement of said rack, and a sheet actuated pendulum provided with a pawl for engaging said ratchet, said reciprocable rack being provided with driving means 75
15 embodying a member with relatively movable parts and yieldable means for normally retaining said parts in fixed positions relative to each other, said yieldable means being adapted to yield when the ratchet is 80
20 engaged by the pawl.

- 25 15. In a sheet feeding machine, a surface over which sheets are fed, a roller adapted to coöperate with said surface in retarding the movement of a sheet, an oscillatory arm which carries said roller into and out of contact with said sheet, a rack bar geared to said roller to rotate the same, means for reciprocating said rack bar, a ratchet bar secured to said rack bar, and a sheet actuated pendulum having a pawl movable into engagement with said ratchet bar. 85

- 30 16. In a sheet feeding machine, a surface over which sheets are fed, a roller adapted to coöperate with said surface in retarding the movement of a sheet, an oscillatory arm which carries said roller into and out of contact with said sheet, a rack bar geared to said roller to rotate the same, means for reciprocating said rack bar, a ratchet bar secured to said rack bar, and a sheet actuated pendulum having a pawl movable into engagement with said ratchet bar, said reciprocating means comprising a rock shaft, an arm keyed thereto, an extension pivotally connected to said arm, and yieldable means for retaining said arm and extension in normally fixed positions relatively to each other. 90

- 35 17. In a sheet feeding machine, a surface over which sheets are fed, a roller adapted to coöperate with said surface in retarding the movement of a sheet, an oscillatory arm which carries said roller into and out of contact with said sheet, a rack bar geared to said roller to rotate the same, means for reciprocating said rack bar, a ratchet bar secured to said rack bar, and a sheet actuated pendulum having a pawl movable into engagement with said ratchet bar, said reciprocating means comprising a rock shaft, an arm 95
40 keyed thereto, an extension pivotally connected to said arm, and yieldable means for retaining said arm and extension in normally fixed positions relatively to each other, said yieldable means being provided with a 100
45 device for adjusting the tension thereof. 105

18. In a sheet feeding machine, a surface over which sheets are fed, an oscillatory lever having an arm movable toward and away from said surface, a roller journaled in said arm, a gear rotatable with said roller, 70
50 a support depending from said arm, a rack in engagement with said gear, said rack being slidably mounted in said depending support, and sheet actuated means for interrupting the movement of said rack. 75

19. In a sheet feeding machine, a power driven arm, a reciprocatory rack bar journaled thereon adjacent one end, an oscillatory lever, a roller journaled thereon, a geared connection between said roller and rack bar, means for raising and lowering said rack bar to maintain said connection during the rise and fall of said roller, and sheet actuated means for arresting the reciprocatory movement of said rack bar. 80

20. In a sheet feeding machine, a power driven arm, a reciprocatory rack bar journaled thereon adjacent one end, an oscillatory lever, a roller journaled thereon, a geared connection between said roller and rack bar, means for raising and lowering said rack bar to maintain said connection during the rise and fall of said roller, and sheet actuated means for arresting the reciprocatory movement of said rack bar, said sheet actuated means comprising a pendulum having a pawl movable therewith and a ratchet bar adapted to be engaged by said pawl, said ratchet bar being connected to said rack bar. 90

21. In a sheet feeding machine, a power driven arm, a reciprocatory rack bar journaled thereon adjacent one end, an oscillatory lever, a roller journaled thereon, a geared connection between said roller and rack bar, means for raising and lowering said rack bar to maintain said connection during the rise and fall of said roller, and sheet actuated means for arresting the reciprocatory movement of said rack bar, said sheet actuated means comprising a pendulum having a pawl movable therewith and a ratchet bar adapted to be engaged by said pawl, said ratchet bar being connected to said rack bar, said pendulum being pivoted 110
115 upon an axis which swings about a second axis. 115

22. In a paper feeding machine, the combination with a surface over which paper is to be fed, of an oscillatory lever arm, a paper engaging roller journaled in said arm, a gear rigid with said roller, a rack meshing with said gear, another oscillatory lever arm connected to said rack, a ratchet bar also connected to the last mentioned lever arm, and a sheet actuated pawl for blocking the movement of said ratchet bar. 120

23. In a paper feeding machine, the combination with a surface over which paper is to be fed, of a lever pivotally mounted to 130

rise and fall relatively to said surface, a paper-engaging roller journaled in said lever, a reciprocatory bar suitably connected to said roller to rotate it on its axis, another reciprocatory bar partaking of the movement of the first mentioned bar, and sheet actuated means for positively locking the reciprocal movements of said bars.

5

also partakes of the forward movement of said sheet, a link pivoted at one end on a fixed axis, and a sheet actuated pawl pivotally mounted on the other end of said link, said pawl being movable into engagement with said ratchet bar to arrest the movement of said sheet-engaging surface of the sheet-feeding instrumentality.

10

24. In a combined slow-down and sheet-straightening machine, a sheet-feeding instrumentality provided with a sheet-engaging surface which partakes of the forward movement of a sheet, a ratchet bar which
